UNITED STATES PATENT OFFICE

123,251

DESIGN FOR AN AIRPLANE

Mac Short and Robert E. Reedy, Glendale, Calif.,
assignors to Vega Airplane Company, Burbank,
Calif., a corporation of California

Application November 22, 1938, Serial No. 81,279

Term of patent 14 years

To all whom it may concern:

Be it known that we, Mac Short and Robert E. Reedy, citizens of the United States, residing at Glendale, in the county of Los Angeles, State of California, have invented a new, original, and ornamental Design for an Airplane, of which the following is a specification, reference being had to the accompanying drawing, forming a part thereof.

Figure 1 is a plan view of an aeroplane embodying our new design.

Figure 2 is a front elevation thereof.

Figure 3 is a side elevation thereof.

Figure 4 is a perspective view viewed from above and at an angle to the fuselage.

Figure 5 is a perspective view thereof viewed from below and at an angle to the fuselage and illustrating the landing wheels retracted.

Figure 6 is an enlarged side elevation illustrating the landing gear in advanced position.

This application is a continuation in part of our application, Serial No. D-75,342, filed February 23, 1938.

We claim:

The ornamental design for an airplane, as shown.

MAC SHORT.
ROBERT E. REEDY.
